UNITED STATES PATENT OFFICE.

EDWARD E. KENNEDY, OF BRIDGETON, NEW JERSEY.

AMUSEMENT APPARATUS.

Application filed March 18, 1922. Serial No. 544,811.

To all whom it may concern:

Be it known that I, EDWARD E. KENNEDY, a citizen of the United States, residing at Bridgeton, in the county of Cumberland and

5 State of New Jersey, have invented certain new and useful Improvements in Amusement Apparatus, of which the following is a specification.

My invention has reference to amusement 10 apparatus of the type known as racing apparatus, which may be used as a means of competitive sport and exercise, and which is especially adapted for use at pleasure resorts, parks, etc.

15 These objects, and other advantageous ends which will be described hereinafter, I attain in the following manner, reference being had to the accompanying drawings in which—

20 Figure 1 is a plan view of my improved amusement apparatus,

Figure 2 is a sectional side elevation of the apparatus, taken on the line 2—2 of Figure 1,

25 Figure 3 is an end view or front elevation illustrating a fragmentary portion of the apparatus embodying a plurality of units,

Figure 4 is a fragmentary plan view showing 30 a portion of a track of one unit and indicating the manner of actuating the various switches for closing the circuits to the lamps, the parts shown being the switch at the starting and finishing point,

Figure 5 is an enlarged transverse vertical 35 sectional elevation taken on the line of the section line 5—5 of Figure 2 of the drawings,

Figure 6 is an enlarged fragmentary horizontal sectional elevation taken on the plane 40 of the line 6—6 of Figure 2,

Figure 7 is a sectional elevation corresponding to Figure 5 but taken on the plane of the sectional line 7—7 of Figure 2,

45 Figure 8 is an enlarged fragmentary perspective view showing the manner of mounting a miniature bicycle upon an endless carrier or chain serving as means for causing the travel of the miniature objects or bicycles around the various tracks, and

50 Figure 9 is a plan view showing the wiring diagram and the relation thereof to the track of a unit.

55 Referring to the drawings in detail, in which for the sake of illustration is shown the preferred embodiment of the invention, and in which like characters designate corre-

sponding parts throughout the several views, my improved amusement apparatus, is shown as comprising a series of units A, B, C, etc.; it being understood that any desirable number of units may be employed and since each unit is of the same construction, a description of one will suffice.

An elongated table or board 10 supported upon corner legs 11 is arranged to simulate or depict a race track or speedway in miniature and each table, suitably constructed of one or more sections, is provided with a continuous slot 12 through the same, said slot being in the form of an oval correspondingly elongated. The table further includes bottom walls 13 arranged adjacent each end and to which the top 10 is secured in spaced relation through the medium of suitable spacing members or blocks 14 at the ends of the top 10 and at points spaced therefrom adjacent to said ends. The legs 11 are suitably braced to the table bottom walls 13 and may be anchored to the floor in any suitable manner such as indicated in the drawings, diagonal braces 15 being shown extending between the free inner ends of the bottom walls 13 and said legs.

A shaft 16 is journaled vertically at one end of the table or track between the top and bottom walls 10 and 13 and has mounted thereon a sprocket wheel 17; the sprocket wheel being confined between the spacing members 14 and having trained thereon an endless carrier or chain 18, the laps of which operate through slots 19 cut in the inner spacing members or walls 14 at each end of the track. A shaft 20 is similarly mounted at the other end of the track or table, except that it is projected downwardly and suitably journaled in a bearing mounted on the floor as indicated at 21 and has fixed thereto a sprocket wheel 22 around which the endless carrier or chain 18 is correspondingly trained between the top and bottom walls 10 and 13 after extending through the slots 19 already described.

Mounted upon each of the endless carriers, belts or chains 18 is a miniature object represented in the present instance as a bicycle 23, preferably of the racing type and adapted to travel with the carrier around the slot 12 of the track. In order to mount the miniature bicycle in position, the endless carrier or chain 19 has one of its links produced with a plate 24 having spaced uprights 25 provided with a cross connecting pin 26 to which

the frame of the miniature bicycle is attached as clearly shown in Figure 8 of the drawing. The uprights 25 are designed to project upwardly through the slot 12, being accommodated for free movement therein, out of contact with the opposite edge walls of the slot. In this connection, it is to be observed from Figure 5 of the drawings, that suitable bearings 27 are provided for the respective shafts 16 and 20 at the top and bottom walls of the track, so as to support the sprocket wheels and chain engaged thereon in spaced relation to said walls so that the uprights will project upwardly therefrom to operate through the slot 12 as described and disclosing to view only the miniature bicycle 23 above the track, while the operating parts described are hidden from view. In this way, the miniature bicycles will act as pointers to indicate the relative positions of the contestants upon the various tracks of the units and at the same time simulate the bicycles, it being understood that dummy riders may be provided thereon if desired or that other suitable devices may be employed for this purpose and for carrying the same.

Fixed upon the shaft 20 is a relatively large beveled or miter gear 28, the same meshing with a relatively small bevel gear 29 fixed on one end of a shaft 30 journaled in spaced upright bearings 31 mounted upon the floor or platform upon which the device may be supported in practice. Fixed to the horizontal shaft 30 is a sprocket wheel 32, which turns between said bearings, said sprocket wheel having trained thereon an endless drive member or chain 33, also trained on a sprocket wheel 34 of a bicycle 35, preferably a large imitation bicycle. The bicycle 35 is supported in any suitable manner upon the floor as by brackets 36 and the drive sprocket thereon has no connection with either wheel as is usual in bicycle constructions. It will thus be noted that the wheels of the bicycle do not rotate, said wheels on the other hand being free or omitted entirely so long as the frame is suitably supported in a stationary position adjacent to one end of the table or track in the manner clearly shown in Figures 1, 2 and 3 of the drawings. The sprocket wheel 34 is preferably smaller than the sprocket wheel 32 and in connection with the gears 28 and 29 produces a reducing gear so that when the operator is seated upon the bicycle 35 and pedals the same through the medium of the pedals 37, a motion will be transmitted through the drive connection to the endless carrier or chain 18 so that the speed of movement imparted to the latter will be relatively slow; the propulsion serving to drive the miniature bicycle around the track by the gearing so as to require a definite time, say one minute, to complete the circuit.

Each unit is provided with a signal sys-

tem or arrangement to indicate the starting and finish of a race and to indicate various positions of the miniature bicycles in circling the track; the same being arranged as shown in connection with Figures 1 to 4 inclusive and the wiring diagram being shown in Figure 7.

Adjacent to the starting and finishing position and other various positions of the race as will be subsequently pointed out, there are located suitable switches and signal devices included in an electrical circuit and adapted to indicate visually or otherwise the start and finish as well as the winner of the race, and when a miniature bicycle passes the first quarter, second quarter or half, and third quarter of the circuit, the signal device mounted at the start and finish point is indicated generally at 38, the signal at the first quarter is indicated at 39 and the signals at the second quarter or half and third quarter are indicated at 40 and 41 respectively. Each of these signal devices includes a switch box 42 in which is mounted a switch blade 43 on the pivot 44 adapted to engage a standard contact 45 and being normally held out of engagement therewith and in the path of the miniature bicycle 23 across the slot 12, so as to be intercepted by the uprights 25 as the latter pass. As shown, a spring or other suitable retracting device 46 connects the switch blade to the switch box, which latter is mounted adjacent the rear end of the table or track. Since the switches 39, 40, and 41 are of similar construction, a description of the switch 38 will suffice. However, it will be stated that there are mounted on the switch boxes or adjacent thereto suitable signal device, preferably visual and shown in the form of electric lamps 47, 48, 49 and 50 designed to be illuminated as the miniature bicycles pass the companion switches. A unit lamp 51 is also adapted to be closed in connection with the lamp 47 and its companion switch 48 and said lamps 51 of the several units composing the device, and of which there may be any number other than three as shown in Figure 1 of the drawings, are mounted upon an upright electric or sign board 52 supported upon the floor in spaced relation to the ends of the tables or tracks, remote from the large imitation bicycles 35 upon which the contestants are adapted to be seated, such as through the medium of standards 53.

The wiring diagram for the signal device is shown in Figure 9 of the drawings, from which the various positions of said devices with respect to the track or speedway produced by the slot 12 will be readily observed. A source of electrical current supply illustrated as batteries 54 is connected to the signal device or lamp 47 through the medium of a line wire or conductor 55,

which extends from the lamp to the terminal of the switch blade 43. A conductor 56 leads from the other terminal 45 to the other side of the batteries and has interposed in 5 the connection, a control switch 57 for the entire system. The lamp 51 is connected in series with the lamp 47 through the medium of conductors 58 and 59 as shown; the lamp 48 is cut in on the conductors 55 and 56 through 10 the medium of the wires 60 and 61; the lamp 49 is cut in on the conductors 55 and 56 through the medium of the wires 62 and 63 and the lamp 50 by means of the wires 64 and 65, each including the companion 15 switch by which the adjacent lamp is controlled.

The pedals 37 of the various bicycles 35 are normally locked in position or held against movement by levers 66 fixed to a 20 common shaft 67 journaled in bearings 68 upon the floor beneath the drive sprockets of the several bicycles 35 so as to engage the pedals in the manner shown in Figures 1, 2 and 3 of the drawings. It will be observed 25 that the shaft 67 is common to all of the bicycles 35 so that the levers 66 can be simultaneously controlled as through the medium of a throw lever 69 mounted at one end of the shaft whereby the pedals may be simultaneously released to insure that all operators of the bicycles or riders acting as contestants will start in unison. In this connection it is pointed out the throw lever 69 is designed to be controlled or released by 30 an official starter so as to insure that the apparatus will serve as a proper test for the efficiency and endurance of the contestants.

In the use and operation of the device, the contestants are seated upon the saddles 40 of the bicycles 35 and the miniature bicycles 23 are moved by propelling the pedals so that all of them will be disposed adjacent to the start and finish line designated by the signals 47. In this position the uprights 25 45 will form engaging members to swing the switch blades 43 into engagement with the terminals 45 and close the electrical circuits including the source of energy to the lamps 47 and 51; thus showing that all of the contestants are ready to start; it being understood that the switches 57 have been previously closed and the pedals are so set as to be located in similar positions when engaged 50 by the holding or locking devices constituted by the levers 66 and their controlling means and also that the miniature bicycles 55 will be positioned as shown in Figures 1 to 4 inclusive of the drawings. The pedals are then released and the various unit lamps 47 and 51 will be extinguished as soon as the engaging or abutment members 25 pass and release the switches. As the bicycles are 60 propelled by the various persons seated upon the same, the miniature bicycles will be moved to traverse the track or circuit there-

of and in passing the various switches and signal devices located at the first quarter, second quarter and third quarter of the circuits, will close said switches and the circuits controlled thereby through the source 70 of energy 54, thus illuminating the respective lamps. These switch are interposed in the paths of the miniature bicycles of each unit and as the miniature bicycles pass they engage the switches and temporarily close 75 the same to cause the flashing of the adjacent lamps and will be automatically released and the lamps extinguished.

As the miniature bicycles approach the starting points, the one first arriving at the 80 finish line will again actuate the corresponding switch so as to close the circuits through the lamps 47 and 51 whereby the winner will be indicated. Thus, it will be seen that this device affords not only amusement but exercise which is a source of both pleasure and competitive effort, the exercise being healthful. The reducing gear between the 85 large imitation bicycles upon which the various persons are seated and between the driving means and the driving means to the carriers or belts 18, is of such character that the bicycles will be operated for some time, say one minute, in order to cause the miniature bicycles to encircle the tracks so that the miniature devices will move relatively slow while the speed at which the mechanism is driven is comparatively high; thus rendering it possible to clearly discern the 90 movement and positions of the miniature bicycles, which serve as indicators of the relative competitive efforts of the contestants instead of permitting said devices to race in such a manner to render their 95 100 relative positions indeterminable.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. Amusement apparatus consisting of a series of tables having endless trackways of equal length; endless carriers mounted to travel under the trackways; toy racing objects connected with the carriers and adapted to travel in the trackways; means for imparting motion to the carriers; a series of pedal actuated sprockets; a second series of sprockets, each operatively connected with a sprocket of the first series; a shaft carrying a series of levers each adapted to engage a pedal; means for actuating the shaft whereby the pedals may be simul- 120 125 130

stantaneously released, and connections between the second series of sprockets and the carrier actuating means whereby the carriers will be driven at a speed having a fixed relation 5 to the speed with which the pedals are actuated.

2. Amusement apparatus consisting of a series of tables having endless trackways of equal length; endless carriers mounted 10 to travel under the trackways; toy racing objects connected with the carriers and adapted to travel in the trackways; means for imparting motion to the carriers; a series of pedal actuated sprockets; a second 15 series of sprockets, each operatively connected with a sprocket of the first series; a shaft disposed under the pedal actuated

sprockets and carrying a series of levers each adapted to engage a pedal; a throw lever for actuating the shaft whereby the 20 pedals may be simultaneously released, and connections between the second series of sprockets and the carrier actuating means whereby the carriers will be driven at a speed having a fixed relation to the speed 25 with which the pedals are actuated.

In testimony whereof I have signed my name to this specification in the presence of two subscribing witnesses.

EDWARD E. KENNEDY.
